(57) **CLAIM**

We claim the ornamental design for a crayon wheel, as shown and described.

DESCRIPTION

FIG. 1 is a perspective view from the bottom, right side and rear of a crayon wheel showing my new design.

FIG. 2 is right side elevational view thereof, the left side elevational view being a mirror image thereof.

FIG. 3 is front elevational view thereof.

FIG. 4 is rear elevational view thereof.

FIG. 5 is top plan view thereof; and,

FIG. 6 is bottom plan view thereof.

The stippling shown on the crayon portions around the perimeter are provided to represent a contrast of color.
